UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

PROCESS OF PURIFYING AND DEHYDRATING TRANSFORMER OIL.

1,425,645.

Specification of Letters Patent. Patented Aug. 15, 1922.

No Drawing.

Application filed May 3, 1921. Serial No. 466,495.

To all whom it may concern:

Be it known that I, CYRUS HOWARD HAPGOOD, a citizen of the United States, and resident of Nutley, county of Essex, and 5 State of New Jersey, have invented a new and useful Improvement in Processes of Purifying and Dehydrating Transformer Oil, of which the following is a full, clear, and exact description.

10 The flow of current through a static electric transformer causes so rapid a rise in temperature that the heat cannot be radiated by air cooling. Hence it is customary to immerse the transformer in oil, which 15 absorbs the heat as it is generated. The oil is contained in a casing having a relatively large surface exposed to the air, which absorbs the heat from the oil as rapidly as the oil absorbs heat from the transformer. This 20 oil is known as "transformer oil".

It is essential that this transformer oil shall be of very high dielectric strength, to secure which it must be almost absolutely dehydrated. In use, the oil gradually 25 absorbs moisture, which, although it accumulates slowly and at no time reaches more than a very small proportion, nevertheless so far lowers the dielectric strength of the oil as to necessitate its re-dehydration.

30 Any oil containing a substantial percentage of free water may be purified, to the extent of removing the larger part of the water, by prolonged settlement by gravity. The most prolonged settlement, however, 35 will still leave in the supernatant oil a proportion of water not substantially less than one-quarter of one per cent or 2500 parts to the million. For many purposes this degree of purification suffices. Where a still further 40 purification is desired, it may be effected by centrifugation in any machine of the cream separator type, wherein water will escape from one outlet and oil from another. However, the percentage of moisture even in used 45 and contaminated transformer oil is far below the percentage of water that will resist elimination by gravity treatment; while the specific centrifugal treatment when conducted in the most effective type of centrifuge specified, yields an oil of scarcely 50 greater dielectric strength than transformer oil that has been contaminated by prolonged use, and therefore not approximating the dielectric strength demanded by electric power plants for fresh transformer oil. In

other words, used transformer oil requiring dehydration contains far less moisture than oil after it has been dehydrated to the greatest extent possible by gravity, while the specified centrifugal treatment is ineffective to reduce the proportion of water to the extent required to meet the requirements for fresh transformer oil. 60

Resort, therefore, has been had to filtration. The filter generally in use comprises a 65 large number—say 1000—sheets of blotting paper. The oil to be dehydrated is forced under pressure through the composite blotter. It is usually necessary to pass the oil successively through a plurality of blotter 70 presses. The dehydrating effort is remarkable, the percentage of water being reduced to (say) nine or ten parts of water to the million parts of oil. The dielectric strength of the dehydrated oil will vary, but may 75 reach 47,000 volts, or substantially in excess of the actual requirements. The process is fairly expeditious, the blotter presses being capable of dehydrating about seven hundred gallons of oil in five or six hours. Where a 80 plant contains but one blotter press, it is usually necessary to run the oil through the same press a plurality of times, which multiplies the time required for complete dehy- 85 dration.

However, this process is open to serious objections. Certain minute shreds and particles of blotting paper are found suspended in the dehydrated oil. These particles collect on the transformer coils and form a 90 coating retarding the transfer of heat. Moreover, in each operation, a certain percentage of the paper units of the blotter press tear or break, due to their moisture content. These must be frequently replaced 95 at considerable cost for both material and labor. 85

The object of my invention is to provide a new method of dehydration whereby at least an equal degree of dehydration may be secured, a much larger volume of oil handled within a given time and the expense and labor of upkeep of the dehydration apparatus so far reduced as to be practically eliminated. 100

I attain this object by subjecting the oil to be dehydrated to centrifugal force while continuously introducing fresh quantities of the oil, providing for the continuous outflow of the oil which, under the influence 105 110

of centrifugal force, has been dehydrated, and confining the water from escape so that the flow of water that forms at the periphery gradually increases in thickness as the 5 process proceeds.

In the ordinary single chamber open bowl centrifugal clarifier, the object is to carry off all the liquid, only the solid or semi-solid ingredients remaining in the bowl. 10 These solids, which accumulate on the bowl wall, are, from time to time, removed by interrupting the clarifying process and cleaning them out. If such a bowl be used for carrying out my process, the water will 15 tend to be forced out to the periphery and remain there, but a very small percentage of the water will flow out with the oil and the maximum dehydration obtainable will scarcely exceed that represented by a 20 electric strength of 35,000 volts, which, in some cases, would be a permissible degree of dehydration, but would not meet the standard exacted in many cases.

The ordinary cream separator of the 25 known multiple disc type is not available to secure the degree of dehydration desired. If a water seal for the heavy liquid discharge outlet is initially established, a large percentage of water is removable, but the 30 desired degree of dehydration is not obtainable, because the oil is not initially distributed around the periphery so as to insure the subjection of all the oil to the maximum centrifugal force.

35 While a single chamber open bowl clarifier is permissibly usable in some cases, I prefer to take a bowl of the type shown in the Snyder Patent No. 1,283,343, October 29, 1918 (which is especially adapted to 40 separate solid ingredients and a heavy liquid from a light liquid) and plug up the outlet for the heavier ingredients. In this separator, provision is made for initially distributing the oil throughout the peripher- 45 al part of the bowl, and the cone disc liner divides the bowl into a multiplicity of separating compartments, wherein the oil is subjected to multiple centrifugations, insuring the elimination of the maximum 50 percentage of water before the oil is free to escape. Moreover, these discs afford a large area for catching and holding any impurities, such, for instance, as particles of dirt, or fine shreds of blotting paper that have 55 been carried off by oil that has previously been dehydrated by filtration through a filter of the blotter press type.

In operation, the oil to be dehydrated is inflow continuously. The water is carried 60 to the periphery of the bowl, from which escape is impossible, owing to the plugging up of the heavy liquid discharge. During the first part of the process the film of liquid which builds up around the peripheral 65 wall of the bowl is of negligible thickness.

This thickness gradually increases as the process proceeds; but owing to the very small proportion of water in the oil, a very large volume of oil may be treated without increasing the thickness of the water envelope to an extent that essentially diminishes the capacity of the separator. When a disc centrifugal is used, I prefer to so space the periphery of the disc liner from the wall of the bowl as to insure that the 75 wall of water will not build up so as to overlap the periphery of the liner.

I have also found it possible to utilize a centrifugal clarifier of the multiple chamber type, for example, a clarifier in accordance 80 with the Leitch Patent No. 1,370,326, March 1, 1921, which is utilized for the purpose of removing solid impurities from a liquid. Such a bowl affords an inner chamber for the collection of the heavier sediment. From 85 this inner chamber there is an escape near the axis of the bowl for the liquid that has been partially desedimentized. If transformer oil is run into such a bowl, most of the water will remain in the inner compartment, while 90 the dehydrated oil will outflow over the central weir and escape into the outer compartment. In this compartment most of the remainder of the water is eliminated. The degree of dehydration in such a bowl is su- 95 perior to that obtainable in an ordinary clarifier or in an ordinary cream separator but is not equal to that obtainable in a bowl of the Snyder type with the outlet for the heavy ingredient closed unless it is equipped 100 with a multiple disc liner.

By the use of my improved process, if carried out in the preferred character of separator, I am able to dehydrate seven 100 hundred gallons of transformer oil in about two and one-half hours or less than half the time required to dehydrate the same quantity of oil by forcing the same through a blotter filter. Careful tests show the dielectric strength of the dehydrated oil to be 11 about 53,000 volts or in excess of that obtainable by the old method. Moreover, my process eliminates all solid particles, including dirt, and also any paper particles that may have been taken up by transformer oil 11 that has been dehydrated by the described filtration process. The power required to operate the centrifuge is less than that required to force the oil through a blotter filter. The expense of upkeep is entirely 12 negligible.

Having now fully described my invention what I claim and desire to protect by Letters Patent is:

1. The process of continuously and practically completely dehydrating oil, such as transformer oil, containing a relatively very small proportion of water, which comprises subjecting the inflowing oil to be dehydrated to centrifugal force whereby the water there- 13

in will be carried to the periphery, confining the water from escape throughout the process so as to build up as the process proceeds a surrounding film or envelope of water of 5 gradually increasing thickness but of a maximum thickness relatively small in comparison with the thickness of the remaining body of liquid that at any given time during the process is being subjected to said force, 10 and while the oil is inflowing and is being subjected to said force floating off the oil from which the water has been eliminated at a point substantially closer to the axis of rotation than the inner wall of the water 15 when the latter is of maximum thickness.

2. The process of continuously and practically completely separating a mixture of a relatively great proportion of relatively light liquid and a relatively small proportion 20 of relatively heavy liquid, which comprises subjecting an inflowing mixture of such liquids to centrifugal force whereby the heavier liquid will be carried to the pe-

riphery, confining the heavier liquid from escape throughout the process so as to build 25 up as the operation proceeds a surrounding film or envelope of heavier liquid of gradually increasing thickness but of a maximum thickness relatively small in comparison with the thickness of the remaining body 30 of liquid that at any given time during the process is being subjected to said force, and while the mixture is inflowing and being subjected to said force floating off the lighter liquid from which the heavier liquid has 35 been eliminated at a point substantially closer to the axis of rotation than the inner wall of the heavier liquid when the latter is of maximum thickness.

In testimony of which invention, I have 40 hereunto set my hand, at New York, on this 28th day of April, 1921.

CYRUS HOWARD HAPGOOD.
